[57] CLAIM

The ornamental design for a dot sight for a range finder, as shown and described.

DESCRIPTION

FIG. 1 is a front elevational view of a dot sight for a range finder showing my new design;

FIG. 2 is a top plan view thereof;

FIG. 3 is a rear elevational view thereof;

FIG. 4 is a bottom plan view thereof;

FIG. 5 is a right side elevational view thereof, the left side is a mirror image; and,

FIG. 6 is a perspective view thereof, the broken line showing of the range finder is for illustrative purposes only and forms no part of the claimed design.
